(57) **CLAIM**

The ornamental design for a hacksaw, as shown and described.

DESCRIPTION

FIG. 1 is a front-left top perspective view of our hacksaw according to our new design;

FIG. 2 is a rear-left top perspective thereof;

FIG. 3 is a rear-left bottom perspective view thereof;

FIG. 4 is a front-left bottom perspective thereof;

FIG. 5 is a left-side view thereof;

FIG. 6 is a right-side view thereof;

FIG. 7 is front view thereof;

FIG. 8 is a rear view thereof;

FIG. 9 is a top plan view thereof; and,

FIG. 10 is a bottom plan view thereof.

The broken lines depict portions of the hacksaw in which the design is embodied that are not considered part of the claimed design.

The dash-dot-dash broken line defines a boundary of the claimed design and is not an ornamental part of the design itself.

Conventional shading is illustrated for purposes of highlighting the line drawings, but forms no part of the claimed design.
